UNITED STATES PATENT OFFICE

CELESTINO ROSATELLI, OF TURIN, ITALY, ASSIGNOR TO FIAT SOCIETÀ ANONIMA, OF TURIN, ITALY

AIRCRAFT DOOR

Application filed December 11, 1930, Serial No. 501,715, and in Italy October 21, 1930.

This invention relates to a door arrangement more particularly for aircraft which permits the normal opening of the door from either side and, in emergency cases when a prompt and easy opening of the door is required for the exit of the driver and passengers, the removal of all the hinge pins from their sockets so that the door is fully set free and can be thrown to the outside.

10 The accompanying drawing shows by way of example a construction of the device according to this invention.

Figure 1 is an elevation showing the device when the door is in its normal closed position.

Figure 2 is a similar view with the hinges disassembled only on the left side for permitting the normal opening of the door on the hinges of the right side (not shown for simplicity's sake).

Figure 3 is plan view on a larger scale showing the central operating mechanism and the safety devices.

1s and 1d denote the hinge pins on the left side and right side of the door, respectively, and 2s and 2d are the hinge-pin sockets which form together with the pins the hinges or joints on which the door is hung.

Since the actuating members for the pins 1s and 1d are identical and symmetrically disposed with respect to the central axis, only the left part of the device will be described. The actuating means of the pins 1d of the right side will be designated by the same reference numerals as the corresponding means of the left side with the addition of a prime (') to said numerals.

The hinge pins 1s are connected together by a rod 3. The rod 3 carries a pin 4 engaging the forked end of the arm 5 of the bell-crank lever 5-7 fulcrumed at 6, and the other arm 7 of which is provided with a slot engaging the pin 8 of rod 9 slidable in guides 10. The rod 9 ends in a fork 11 slotted for receiving the pin 13 of the roller 12 which is thus capable of an axial displacement by the extent allowed by the slot. The rods 9 and 9' are arranged parallel to each other.

50 A spiral spring 14 acting on the ring 15 secured to the rod 9 tends to move said rod until

the ring 15 rests against the corresponding guide 10, a bell-crank lever is fulcrumed at the fixed point 16, and has an arm 17 engaged by the pin 13 of the roller 12, while the other arm 18 ends in a hook 19 which, in its 55 normal position, abuts the projection 20 of the rod 9.

A spring 21 holds the hook 19 engaged with the projection 20. A cam or lever 22 is rotatably mounted on a pin 23 and can be acted 60 upon by means of a suitable hand lever (not shown).

The lever 22 is adapted to lift the hinge pins 1s for the normal opening of the door on its left side, while the lever 22' is adapted 65 to act on the hinge-pins 1d and to lift these latter for the normal opening of the door from its right side. In emergency cases, by acting upon both hand levers both levers 22 and 22' shall be displaced setting the door 70 free on both sides.

The bell-crank lever 17-18 serves as a safety stop against undesired displacement of the rod 9.

When the lever 22 is acted upon and the 75 lever 22' is left stationary, as shown in Fig. 2, the roller 12 is first displaced, the pin 13 whereof slides in the elongated slot on the rod 9 (which remains stationary) while the bell-crank lever 17, 18 is swung out of the projection 20, so that the further movement of the lever 22 causes the rod 9 to slide and releases the hinge pins 1s on the left side, while the hinges on the right side remain in place and serve to support the door. When it is desired 85 to disassemble the hinges on both sides, the levers 22 and 22' are operated as previously described and the hinge pins 1d and 1s will be withdrawn from their sockets.

What I claim is:

1. A combined hinge and latch device for doors, comprising, in combination with hinge sockets adapted to be fixed to the two frame ledge portions of a door and with rods adapted to be mounted axially displaceable on the sides of a door and carrying the hinge pins, an actuating device for said rods consisting of a push rod for each of said hinge pin carrying rods, a bell-crank lever for connecting each push rod with its respective hinge pin 100

carrying rod, levers operated by hand for actuating said push rods and means for locking said rods in position for holding said hinges assembled, said means being released 5 automatically through the operation of said hand-operated levers.

2. A combined hinge and latch device for doors, comprising, in combination with hinge sockets adapted to be fixed to the two frame 10 ledge portions of a door and with rods adapted to be mounted axially displaceable on the sides of a door and carrying the hinge pins, an actuating device for said hinge pin, carrying rods consisting of a push rod for each 15 hinge pin carrying rod, a bell-crank lever for connecting each push rod with its respective hinge pin carrying rod, oscillating lock members which normally lock the push rods in position for holding said hinges assembled, pin and slot connections of said oscillating member and of said push rods and 20 hand-controlled cams acting on said push rods through said oscillating lock member, so as to release first said push rods from said lock members, and thereupon to displace said push 25 rods.

In testimony that I claim the foregoing as my invention, I have signed my name.

CELESTINO ROSATELLI.
